(57) **CLAIM**

The ornamental design for an identity sensor as shown and described.

DESCRIPTION

FIG. 1 is a top, right and front perspective view of the identity sensor showing the new design;

FIG. 2 is a left elevation view of the identity sensor in FIG. 1, in accordance with the present invention;

FIG. 3 is a front elevation view of the identity sensor in FIG. 1, in accordance with the present invention;

FIG. 4 is a right elevation view of the identity sensor in FIG. 1, in accordance with the present invention;

FIG. 5 is a top elevation view of the identity sensor in FIG. 1, in accordance with the present invention;

FIG. 6 is a rear elevation view of the identity sensor in FIG. 1, in accordance with the present invention; and,

FIG. 7 is a bottom elevation view of the identity sensor in FIG. 1, in accordance with the present invention.

The broken lines in the drawings depict portions of the identity sensor that form no part of the claimed design.

1 Claim, 3 Drawing Sheets
